Assistant Examiner — Melissa A Santos

CLAIM

The ornamental design for a ceiling fan with light as shown and described.

DESCRIPTION

FIG. 1 is a front and top perspective view of the ceiling fan with light, showing my design

FIG. 2 is a rear and bottom perspective view thereof of FIG. 1;

FIG. 3 is a front view thereof of FIG. 1;

FIG. 4 is a rear view thereof of FIG. 1;

FIG. 5 is a left side elevation view thereof of FIG. 1;

FIG. 6 is a right side elevation view thereof of FIG. 1;

FIG. 7 is an enlarged top plan view thereof of FIG. 1;

FIG. 8 is an enlarged bottom plan view thereof of FIG. 1; and,

FIG. 9 is a front and top perspective view showing the ceiling fan with light in a position of use.

The broken lines depict portions of the ceiling fan with light that form no part of the claimed design.
